UNITED STATES PATENT OFFICE

WILHELM GIEBELE, OF KONIGSTEIN-ON-THE-ELBE, GERMANY

PAPER MACHINE

Application filed May 24, 1930, Serial No. 455,305, and in Germany September 21, 1926.

My invention relates to paper machines having movable Fourdrinier wires and slices at the front end of the machine.

It is an object of my invention to eliminate certain drawbacks of machines of this type as designed heretofore. To this end in addition to the means for removing the water from the pulp by back-pressure at the point where the slices are arranged, I provide further means for the same purpose which extend along the Fourdrinier wire as far as the water in the pulp still permits a variation in the position of the fibres.

In paper machines of the type referred to as designed heretofore the felting of the paper fibres is often unsatisfactory between, and immediately at the rear of, the slices because a considerable percentage of the fibres assumes a position parallel to the direction in which the Fourdrinier wire is moved, under the influence of the flow beneath the last slice. The fibres tend to remain in this parallel position and only comparatively few fibres assume a transverse position. It has already been suggested to eliminate this drawback by effecting hydraulic back-pressure in the space intermediate and immediately at the rear of, the slices so as to prevent removing of the water at this station.

A water trough was provided below the Fourdrinier wire in the vicinity of the slices. By these means the fibres are held suspended and therefore have no tendency to assume a definite position so that satisfactory felting is obtained. However, the fibres are still able to assume an undesirable position at the rear of the slices along the Fourdrinier wire. The danger zone extends as far as there is still so much water in the pulp that the fibres are not in firm engagement with each other.

By providing hydraulic back-pressure means throughout this zone I obtain a positive control of the removing of the water.

Preferably the region of back-pressure at the rear of the slices is subdivided into several independent control ranges.

In the drawings affixed to this specification and forming part thereof a machine embodying my invention is illustrated diagrammatically by way of example.

In the drawings

Fig. 1 is a diagrammatic elevation of the machine,

Fig. 2 is a section on the line II-II in Fig. 1, and

Fig. 3 is a plan view of Fig. 2.

Referring now to the drawings, and first to Fig. 1, only those parts of the machine have been illustrated diagrammatically which are important for the understanding of the invention. *k* is the breast roll, *l* is the couch roll, *d* is the Fourdrinier wire which is supported on, and actuated by, the cylinders, *m*, *m* are guide and table rolls for the upper and lower reaches of the Fourdrinier wire *d*, and *n*, *n* are guide rolls supporting the usual belts *u* which move in parallel with the upper reach of the Fourdrinier wire.

a are the slices, three of which are shown by way of example, *b* is the first water trough below the slices, and *c*, *c* are supplementary troughs which extend throughout the danger zone below the Fourdrinier wire *d*.

Referring now to Figs. 2 and 3, *p* are members of the frame of the machine which extend along the Fourdrinier wire *d*, *h* are guiding blocks on the frame, *g*, *g* are pins secured to the ends of the troughs and adapted to slide in the blocks *h* for shaking the Fourdrinier wire *d*, and *t*, *t* are straps at the ends

extending from the ends of each trough and supported on the frame members *p*. Means are provided for regulating the hydraulic back-pressure in the troughs *c*, such means comprising a slide *f* which is guided in suitable brackets *q* at the bottom of each trough and is perforated at *r*. By means of a handle *s*, the slides *f* are adjusted so that the perforations *r* and *e* in the slides and the troughs

register to a greater or lesser extent, or are closed, as shown in Fig. 2. Means, not shown, might be provided for adjusting the slides *f* in unison but it is preferred to regulate each trough independently as required at the point where such trough is situated.

In the present instance, therefore, the danger zone is subdivided into as many control ranges as there are troughs *c*.

When the slide *f* in a given trough *c* is moved so that the openings *e* in the trough

register fully with the openings *r* in the slide, the water flowing through the Fourdrinier wire from above is discharged through the openings *e*, *r*. When, however, the openings 5 are closed more or less, an increasing resistance is opposed to the discharge of the water, and the water rises in the trough. When it reaches the Fourdrinier wire *d*, it begins to exert a pressure on the pulp from 10 below and to interfere with the flow of the water. The interference is a function of the area *e*, *r* which the corresponding slide *f* has laid open.

The troughs are pitched apart for a distance *i*, which must be selected so as to prevent interference of the troughs with the walls of the adjacent troughs as they are being shaken. The distance *i* should be as small as practicable in order to prevent distortion 15 of the Fourdrinier wire when the troughs are shaken. Preferably the clearance *i* is only about $\frac{1}{16}$ to $\frac{1}{8}$ in.

By means of the arrangement of supplementary troughs *c* at the rear of the first 20 trough *b* below the slices *a* the water conditions in the pulp are regulated throughout the zone in which the percentage of water in the pulp is so high as to influence the relative position of the fibres and the structure 25 of the pulp.

I wish it to be understood that I do not desire to be limited to the exact details of construction shown and described for, obvious modifications will occur to a person skilled 30 in the art.

In the claims affixed to this specification no selection of any particular modification of the invention is intended to the exclusion of other modifications thereof and the right to 35 subsequently make claim to any modification not covered by these claims is expressly reserved.

I claim:—

1. A paper machine comprising a slice, 40 a wire adapted to be moved with respect to said slice, hydraulic back-pressure means arranged in the immediate vicinity of said slice, hydraulic back-pressure means extending from said first-mentioned means part way to 45 the rear along said wire, and means for regulating the flow of water in said first- and in said second-mentioned back-pressure means.

2. A paper machine comprising a slice, a wire adapted to be moved with respect to 50 said slice, hydraulic back-pressure means arranged in the immediate vicinity of said slice, hydraulic back-pressure means extending from said first-mentioned means part way to the rear along said wire, and independent 55 means for regulating the flow of water in said first- and in said second-mentioned back-pressure means.

3. A paper machine comprising a slice, a wire adapted to be moved with respect to 60 said slice a hydraulic back-pressure trough

arranged in the immediate vicinity of said slice, and hydraulic back-pressure troughs extending from said first-mentioned trough part way to the rear along said wire.

4. A paper machine comprising a slice, a wire adapted to be moved with respect to said slice, a hydraulic back-pressure trough arranged in the immediate vicinity of said slice, hydraulic back-pressure troughs extending from said first-mentioned trough part way to 70 the rear along said wire, and means for regulating independently the back-pressure in each of said last-mentioned troughs.

5. A paper machine comprising a slice, a wire adapted to be moved with respect to said slice, a hydraulic back-pressure trough arranged in the immediate vicinity of said slice, and hydraulic back-pressure troughs adapted 80 to be shaken and extending in spaced relation to each other from said first-mentioned trough part way to the rear along said wire.

6. The method of making paper comprising subdividing a layer of pulp into a plurality of independent regulating sections and regulating, by hydraulic back pressure, the 90 removal of water from these sections as far as the water contents of the layer is still so high as to permit variation of the relative position of the fibres.

In testimony whereof I affix my signature. 95
WILHELM GIEBELER.
